UNITED STATES PATENT OFFICE.

THEODORE PEITER, OF NEW YORK, N. Y.

DESIGN FOR A FINGER-RING.

SPECIFICATION forming part of Design No. 12,567, dated November 8, 1881.

Application filed September 9, 1881. Term of patent 7 years.

To all whom it may concern:

Be it known that I, THEODORE PEITER, of the city, county, and State of New York, have invented and produced a new and original Design for Finger-Rings, of which the following is a specification, reference being had to the accompanying drawings, forming part thereof, in which similar letters of reference indicate corresponding parts in all the figures.

10. Figure 1 is a front elevation of my newly designed finger-ring. Fig. 2 is a cross-sectional elevation of the same on the line $y-y$ of Fig. 1. Fig. 3 is a longitudinal sectional view of the same on the line $x-x$, Fig. 1. Fig. 4 is a 15 longitudinal elevation of the same. Fig. 5 is a longitudinal sectional view of a modification of the same.

The finger-ring A is provided with a gem, B, such as an onyx, cameo, &c., the body-surface b 20 of which is flush with the surface of the shanks c —that is to say, the body-surface b of the gem B does not rise from or project above the surface of the shanks c . The gem B is provided at the top and bottom with a ridge, a , rising or 25 projecting from the body-surface b . A figure-head or ornament is cut on the gem in relief or intaglio, or the gem may be plain. The ends of the shanks c are connected by the ridges or recessed edges d , passing along the upper and 30 lower ends of the gem B, the upper surface of these raised edges being flush with the upper surfaces of the ridges a of the gem. From the end of the ridges a of the gem the raised edges d , running along the edges of the shanks 35 c , gradually decrease in height—that is, they gradually taper downward until the upper surfaces of the raised edge are united and flush with the outer surface of the shanks. The

body-surface b of the gem is stippled, as are also the surfaces of the shanks c adjoining the gem, 40 the stipple gradually decreasing toward the narrower part of the ring, as shown in Fig. 4.

The surface of the gem B may be curved the same as the ring A, as shown in Fig. 3, or the surface of the gem may be level, as shown in 45 Fig. 5; but in all cases the body-surface of the gem will not rise above or project from the surface of the shank.

Having thus fully described my invention, I claim as new and desire to secure by Letters 50 Patent—

1. The design for finger-rings herein shown and described, the same consisting of the gem B, the body-surface b of which is flush with the surface of the shanks c and below the raised 55 edges of the shanks, as set forth.

2. The design for finger-rings herein shown and described, the same consisting of the gem B, having its body-surface b stippled and flush with the stippled surfaces of the shanks c and 60 below the raised edges of the same, as set forth.

3. The design for finger-rings herein shown and described, the same consisting of the gem B, having a ridge, a , projecting from the body-surface b at the upper and lower end of the 65 gem, as set forth.

4. The design for finger-rings herein shown and described, the same consisting of the gem B, having at the upper and lower ends a ridge, a , raised from the body-surface b and flush 70 with the raised edges d of the ring, as set forth.

THEODORE PEITER.
